UNITED STATES PATENT OFFICE.

CHENG WEN CHIH, OF CANTON, CHINA.

CALCULATING MACHINE.

Application filed January 31, 1920. Serial No. 355,463.

To all whom it may concern:

Be it known that I, CHENG WEN CHIH, a citizen of China, residing at Canton, China, have invented new and useful Improvements in Calculating Machines, of which the following is a specification.

This invention relates to calculating machines, and one object is to provide a device by the use of which the operations of addition, subtraction, multiplication and division may be performed, as well as other more complicated operations, in a simplified manner, and without the use of elaborate mechanism.

15 A further object is to provide a device which may be manufactured at reasonable cost, and is equally adapted for the use of students and those engaged in solving complicated problems in connection with scientific work.

20 A further object is to provide a device by the use of which the operation of subtraction may be performed on the same principle as that of addition.

25 A still further object is to provide a calculating device employing a plurality of disks each of which carries two series of numerals, the numerals being arranged in reverse order in the respective series, and certain novel means for controlling each disk by the next lower disk toward the right.

30 A still further object is to provide a calculating machine with a suitable casing therefor, of such proportions that it may be readily carried in the pocket of the individual desiring to make use of the device.

With the foregoing and other objects in view, the invention consists in the novel construction, combination, and arrangement of elements hereinafter described and claimed.

In the accompanying drawings,

Figure 1 is a perspective view of the casing for inclosing the device,

Figure 2 is a perspective view of one of the trays, or sections of the casing,

Figure 3 is a perspective view of one of the end members of the casing,

Figure 4 is a top plan view of one of the sections or trays, with the elements of the calculating device mounted therein,

Figure 5 is a bottom plan view of several of the rotatable elements, showing the means for imparting movement to a given disk from an adjacent disk,

Figure 6 is a longitudinal section through

one of the holders received by the trays, the section being on line 6-6 of Figure 4,

Figure 7 is a section on line 7-7 of Figure 6,

Figure 8 is a section on line 8-8 of Figure 6,

Figure 9 is a top plan view of several adjacent disks, each having two series of numbers, reading in the direction shown,

Figure 10 is a top plan view showing the apertured slides which cooperate with the disks,

Figure 11 is an end view of the structure of Figure 1, the end plate of the casing being removed,

Figure 12 is a perspective view of one of the slides, showing fingers on the lower side thereof, for the purpose indicated below,

Figure 13 is a detail view showing the movement of the element by means of which rotation is imparted to the next higher disk.

The casing in which the apparatus is conveniently installed, in order that it may be easily carried or placed in the pocket of the individual making use of it, includes a plurality of sections 10 and 12 these sections being identically formed. The end members 14 are shown in Figure 3 and each includes flanged elements 14' which fit over the ends of the sections of the casing and are secured in any suitable manner, as by means of pivoted hooks 15. Each section or tray is provided with guides of the form shown in Figure 2, and there designated 16, these guides being in pairs having offset portions in the ends thereof, properly secured to the ends of the sections above referred to.

Holders for the operative elements of the device are designated 20, and are each provided on the bottom thereof with inwardly turned flanged portions 21 engaging the aforesaid guides, permitting the holders to slide within the sections of the casing.

Within each holder I mount a series of disks or wheels 24, these elements being rigid with reference to spindles 25, and the latter each being formed with a crank element, or offset element 26, shown in Figure 8, each spindle being further provided with a handle portion and pointer 27, by means of which the disk is readily rotated by the finger of the user of the device.

Each disk or wheel carries on the under side thereof a plurality of pins 28, termed

long pins. There are ten of these pins to each disk.

Considering the disk at the right hand as the unit disk, the latter will make a complete revolution in imparting to the next disk, or tens disk, one-tenth of a revolution, and this relative movement holds good for any two adjacent disks in a given holder, that is in the same longitudinal line. In order to impart this movement, I provide a pivotally mounted plate 30 having an elongated slot 31 at its central portion through which the pivot pin passes.

Plate 30 is provided with slots 32 and 33 proportioned to engage certain of the pins of the adjacent disks, in the manner shown in Figures 5 and 6. The corner portions of the plates 30 which engage the slots are rounded as shown at 33', in order to permit 20 of the return of the elements to normal position. The rounded surface 33' in engagement with one of the pins 28 (Figure 13), acts as a cam and imparts a longitudinal thrust to plate 30 as soon as the pin 40 advances in a counter-clockwise direction 25 slightly from the position of Figure 13, slot 31 permitting this movement. The coiled springs having been tensioned when moving plate 30 from normal position, will now 30 turn that element to the position of Figure 5. It is assumed that the spindles on each of the disks are mounted for frictional contact with their bearings, and that they will remain in the position in which they are set. 35 The pivotal pin 34 of the plate 30 is encircled by coiled spring 35 permitting of the vertical movement of the plate. Springs 37 and 38 connected with opposite ends of the plate and with the base of the holder, tend to 40 hold the plates in normal position, or in the position of Figure 5, and to restore them to that position after being thrown by the manual rotation of the disks or either one of them.

45 This plate 30 is not engaged by the long pins 28 of the actuating disk, but is engaged by a single short pin 40, with the result that this actuating element 30 is only operated once for each complete revolution of a given 50 disk, the elements being so proportioned that the next disk to the left is rotated through one-tenth of a revolution, for purposes well known in calculating devices. The deflected portion 30' of the actuating plates 30 is beyond the path of movement of the short pin 40.

In order to reset the disks, and for the purposes indicated below, I provide the slides 45 and 46 shown in Figure 10 and 60 shown in perspective in Figure 12. One of these slides carries fingers 47 having bevelled ends 47' for engaging the plates 30 and throw them out of engagement with the pins, permitting of the resetting operation.

65 The slides 45 and 46 carry operating ele-

ments 49 by which they may be moved longitudinally, and slide 46 may be moved toward the slide 45 in effecting the operation just mentioned. Slide 46 is provided with slots 58 which engage the crank arms 26, offset in the manner shown in Figure 8, and the movement thereby imparted to the disks is sufficient to restore the latter to normal position, that is, to zero, regardless of the position of individual disks. The crank portion 26 will be engaged by some edge wall of slot 58, and this element 26 is so positioned that when the pointer is opposite any of the numbers of the disk there will be no direct engagement between the end wall of slot 58 and element 26, but always an engagement at some angle, so that sidewise movement of the crank and rotary movement of the disk follows.

Each disk carries an outer series of numerals designated 55, the figures running from 1 to 9, in the direction shown, and being followed by zero. An inner series of numerals 56 runs in the opposite direction, the numeral 4 of this series being opposite zero of the other series. Apertures 57 in slide 45 expose to view one numeral at a time of the outer series, which may be termed the series of positive numbers. The numerals of this series may be in red. The 95 apertures 58 in plate 46 expose to view the numerals of the inner series, and these may be in black, and may be termed negative numbers.

Above the disks are indicating devices 10 shown in Figure 4, and these may be in the form of plates or cards marked 60, and provided with opposite slots 61 and 62 registering respectively with the inner and outer series of figures. Plate 60 is further provided with the representation of a geometrical figure 63 which may be likened to a ten-pointed star.

The slides 45 and 46 are movable longitudinally in one operation by applying the 1 finger to either of the engaging devices 49. Slide 45 has a laterally extending arm 45', and at one end, and slide 46 has an arm 46', and in view of the relation of the elements shown, the slides move together, as stated, 1 when they are shifted lengthwise. In view of the relation between the slots in the slides, and the slots 62 and 61 in plate 60, only one numeral on each disk will be exposed to view at one time. In Figure 10 one of the numerals of the outer series will be exposed to view. When the slides are moved to the left, one figure of the inner series will be exposed.

When it is desired to perform the operation of addition, the disks in the upper row of Figure 4 are preferably used, these disks being first turned to zero, and then rotated manually so that the first number of the example shall appear through the openings

62, each figure of the number appearing on one of the disks in correct position with reference to the adjacent figures, and adjacent disks. The element 27 serves not only as an operating device but as a pointer and cooperates with the figure representing the ten-pointed star.

The second number of the example is preferably shown by the disks of the second row, or middle row reading from left to right. Beginning with the left hand disk of the middle row (and having reference only to the disks which have been set as above), that disk is rotated in clockwise direction as many points as are indicated by the figure exposed to view in the disk directly above. If the number in the first row is 22, the first disk in the second row, or middle row, will be rotated two points, and the same statement applies to the next disk toward the right in the middle row. If the number had been 23, the disk last named would have been rotated three points. The disks of the middle row having been set as stated, the number read from those disks represents the total of the two original numbers.

In the foregoing it will be noticed that the numbers of the outer series of each disk have been used, these representing positive numbers, and not negative or minus quantities.

In subtraction, the first number is preferably represented by the disks of the upper row, and the number to be subtracted is shown by the disks of the lower row. Thus far the numbers are read through the openings 62. If the number to be deducted is not greater than the principal number, then the operator proceeds with the operation above mentioned, under addition, (after shifting slide 46 to the left so the figures will appear through openings 58) adding the number of the inner series 56 appearing in the lower apertures of the lower row to the original number, with the proviso that before adding there shall be an increase of one unit on the last disk to the right in the number to be added (outer series). This increase is obviously secured by continuing the rotary movement until the next higher numeral appears, and not beyond that point.

In the event that all of the disks are not used, 9 must be added to each disk to the left of the vertical row of disks employed in carrying out the operation.

The result thus obtained is also a positive number, shown in the upper apertures.

What I claim is—

1. In a device of the class described, a series of rotatable disks, each disk bearing

an outer series of numerals and a second series of numerals reading in the opposite direction, and interengaging devices longitudinally movable and acting to permit one numeral of either series to be exposed on each disk, to the exclusion of all other numerals on the same disk. 65

2. In a device of the class described, a series of rotatable disks, each disk bearing an outer series of numerals and an inner series of numerals reading in the opposite direction, interengaging devices having openings out of alignment transversely thereof, and a plate having openings in alignment transversely thereof, said openings permitting of the exposure of one numeral of either series of each disk, to the exclusion of all other numerals on the same 30 disk. 75

3. In a device of the class described, a series of numbered disks, devices having openings therein and movable longitudinally of the series of disks, one of said devices including a laterally extending member adapted upon movement in one direction to engage the other of said longitudinally movable devices. 85

4. In a device of the class described, a series of rotatable disks having their axes of rotation parallel, engaging devices carried by the disks, a pivoted element mounted for resilient movement in a plurality of directions, and tiltable at an angle with reference to its plane of movement, said pivoted element cooperating with the engaging devices, and serving to impart movement from one disk to the adjacent disk, and slideable means for throwing the pivoted 100 element out of the path of movement of the engaging devices. 95

5. In a device of the class described, a series of rotatable disks having their axes of rotation parallel, engaging devices carried by the disks, a pivoted element mounted between each two disks and having slotted portions for contacting with the engaging devices of one disk when said element is engaged by certain of the engaging devices of the adjacent disk, resilient means permitting movement of the pivoted element in the direction of its axis, and a spring connected with each end of the pivoted element and serving to normally retain this element in a plane parallel with the disks, to permit angular movement with reference to the surface of the disks, and to restore the latter to normal position when deflected. 115

In testimony whereof I affix my signature. 120

CHENG WEN CHIH.
